Inventor:

Ray A. Thompson

By Joshua R. Cook.

Attorney.

UNITED STATES PATENT OFFICE.

RAY A. THOMPSON, OF CHICAGO, ILLINOIS.

SIGN.

Application filed July 26, 1924. Serial No. 728,317.

To all whom it may concern:

Be it known that I, RAY A. THOMPSON, a citizen of the United States, and a resident of the city of Chicago, county of Cook, and State of Illinois, have invented certain new and useful Improvements in Signs, of which the following is a specification.

My invention relates to signs, the invention being more particularly related to an improved sign construction designed to be employed at street junctions and intersections, on roads and highways, and in such other places and capacities where it may be used advantageously.

The main object of my invention is the provision of a sign construction of this character, designed to employ sign plates mounted one above the other, and to make provision for the interchangeability of the plates.

Another object of my invention is the provision of a sign construction wherein each sign plate is readily adjusted as about an axis, in order to be brought into the best readable relation with the street or place to be identified, and wherein the number of sign plates may be readily increased or diminished in accordance with the requirements of the particular location of the sign.

A further object is to provide an improved sign plate adapted to be cast in one piece with certain joint portions and also with a name in relief on each face.

Objects and features of the invention, other than those specified, will appear hereinafter.

The invention consists in the details of construction and in the arrangement and combination of parts hereinafter described and particularly pointed out in the claims.

For a full understanding of the invention, reference is to be had to the accompanying drawing, forming a part of this application, and in which,

Fig. 1 is a view in perspective of my improved sign construction.

Fig. 2 is a sectional elevation of the improved sign, fractionally shown, the section being taken substantially on the line 2—2 of Fig. 1.

Fig. 3 is a cross section on the line 3—3 of Fig. 2.

With more particular reference to the accompanying drawing, it will be observed that the improved sign construction illustrated, by way of example, consists of a

post 4 on which is mounted a post cap 5 supporting the sign plates 6 and 7, the latter plate being mounted upon the former plate as shown. The post cap and the sign plates 60 are made as one piece elements; preferably cast from aluminum in order to be light in weight as well as strong.

The post cap 5 is made with a hollow base 8 and both this base and the top 9 of the 65 post 4 are made in co-operative angular form in cross section; preferably in the octagonal form shown. Centrally at its top end, the post cap is made with a joint member 10 having a circular rim opening or 70 cavity 11 in communication with a socket 12 immediately therebelow. The wall bounding the socket or cavity 12 is made in angular form; preferably in octagonal form in cross section, in order to provide a large 75 number of angular adjustments for the supporting sign plates as will be presently understood.

The sign plate 6 is cast at its bottom edge midway its length with a depending disk 80 portion 13 and a stud 14 therebelow, the last mentioned being made in octagonal form in cross section, these two members being adapted respectively to fit the circular opening 11 and socket 12. Between the disk portion 13 and stud 14 is an annular recess 15 adapted to receive a set screw 16 whereby to secure the parts together. The sign plate 6 is also cast on either face with raised letters 17 indicative of the street or place to 90 be identified. This sign plate, at its top edge midway its flange, is cast with a socket or joint member 18 which is made precisely like the joint or socket member 10 cast on the post cap. 95

The sign plate 7 is made in all respects like the sign plate 6 except that in the present instance, this sign plate, which is intended to be the topmost sign plate in the construction, is provided at its top edge with an 100 ornamental knob or projection 19 in place of the socket or joint member 18 on the sign plate 6. This sign plate 7, centrally of its bottom edge, is cast with a disk 20, and a stud 21 adapted respectively to fit in the 105 circular opening and octagonal socket of the joint member 18 as shown. On either face the sign plate 7 is cast with raised letters 22 indicative of the place or street which it is intended to identify. 110

In the employment of my improved sign construction the post cap is applied to a

post as shown and is removably secured thereon by a set screw 23. In this connection I may remark that this set screw 23, as well as the set screws 16 employed to secure the sign plates in their socket joints, is preferably made headless; and for its manipulation I contemplate using a special tool in order that the parts will not be readily separated and removed by vandals or other troublemakers. The sign plate 6 is mounted in the socket joint 10 in such manner that the raised letters on its face may be readily readable from the street or roadway which it is intended to identify. Owing to the co-operation of the octagonal form of the stud and the socket joint, the sign plate may be readily adjusted as about an axis in the position best adapted to render conspicuous from the street or roadway the names on the faces of the sign plate. The sign plate 7 is similarly adjusted as about an axis in the socket joint of the sign plate 6. Sign plates as 6 and 7 may be made precisely alike, each having at its lower edge a projecting portion and at its top edge a socket joint in order that they may be interchangeable as to position upon the post cap 5. Where the exigencies of the place or situation require it, the post cap 30 may support, one upon the other, any number of sign plates.

From the foregoing description taken in connection with the accompanying drawing, it will be understood that by means of my improvements I have provided a sign construction embodying unitary sign plates which may be mounted one upon the other, to which construction individual plates may be readily added or from which construction individual plates may be as readily removed, all the plates involving co-operative features of adjustability.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A street sign including a post cap having an upwardly projecting joint member with a socket therein, and a sign plate arranged on said joint member and having a depending part fitting within and interlocking with the socket therein.
2. A street sign including a support, a joint member upwardly projecting therefrom and having a two-part socket therein, and a sign plate having a downwardly pro-

jecting portion freely adjustable in one part of said socket and interlocking with the other part thereof.

3. A sign including a supporting element having a socket member with a portion polygonal in cross section and a portion circular in cross section, a sign plate having a depending member with portions respectively adapted to have bearing in said polygonal portion and said circular portion of the socket member, thereby providing for adjustment of the sign plate in a choice of positions without removing its depending member from said socket member.

4. A sign including a supporting element having a socket member with a portion polygonal in cross section and a portion circular in cross section, a sign plate having a depending member with portions respectively adapted to have bearing in said polygonal portion and said circular portion of the socket member, thereby providing for adjustment of the sign plate in a choice of positions, and means for securing the sign plate in adjusted position.

5. A sign construction having in combination a post, a post cap supported upon the post and having a socket member, and a sign plate cast with a depending portion attached to and bearing in said socket.

6. A sign construction having in combination with a post cap provided with a socket member, a post for supporting the cap, a sign plate cast with a depending portion adjusted to and having bearing in said socket member, and means in connection with the depending portion and socket member to maintain the sign plate in the adjusting position desired.

7. A sign including a supporting element having a socket member, a sign plate cast at its bottom side with a depending stud fitting said socket member and at its top side with a socket member, a second sign plate cast at its bottom side with a depending stud fitting the socket member of the first sign plate and at its top end with a socket member, said depending studs and socket members being of like construction to allow interchanging of the sign plates.

8. A sign construction comprising in combination a post cap provided with a socket member, a post for supporting the post cap, a sign plate having a stud fitting said post cap socket member and having also a socket member, a second sign plate having a stud fitting the socket member of the first sign plate and also having a socket member, said studs and socket members on the sign plates being of like construction to allow substitution of one plate for the other.

9. A sign construction including a supporting element provided at its top with a circular opening and a polygonal socket into which the circular opening merges, and

a sign plate provided with a disk member and a projecting portion adapted respectively to fit said circular opening and said socket.

10. A sign construction including a supporting element provided at its top with a circular opening and a polyangular socket into which the circular opening merges, a sign plate provided with a disk member

and a projecting portion adapted respectively to fit said circular opening and said socket, and means in communication with said projecting portion and the walls of the socket member to maintain the sign plate in any one of a variety of positions.

15 In testimony whereof I have signed my name to this specification.

RAY A. THOMPSON.
